UNITED STATES PATENT OFFICE.

CHARLES D. FAGAN, OF SHARON, PENNSYLVANIA, ASSIGNOR TO SHARPSVILLE BOILER WORKS CO., OF SHARPSVILLE, PENNSYLVANIA, A CORPORATION OF PENNSYLVANIA.

DESIGN FOR A GASOLINE-METER CASING.

Application filed July 28, 1927. Serial No. 22,903. Term of patent 14 years.

To all whom it may concern:

Be it known that I, CHARLES D. FAGAN, a citizen of the United States, residing at Sharon, in the County of Mercer, State of Pennsylvania, have invented a new, original, and ornamental Design for a Gasoline-Meter Casing, of which the following is a specification, reference being had to the accompanying drawing, forming part thereof;

The figure in the drawing is a perspective view of the article showing my new design.

I claim:

The ornamental design for a gasoline meter casing substantially as shown.

CHARLES D. FAGAN.
